AUXILIARY RELOADING PLATE FOR
PRESS FEEDERSGeorge W. Waller and Harry H. Waller,
Dallas, Tex.

Application July 28, 1948, Serial No. 41,068

2 Claims. (Cl. 271—62)

1

This invention relates to automatic printing press feeders and it has particular reference to an auxiliary reloading unit for press feeders.

In the operation of the automatic press feeders much of a pressman's time is consumed in reloading operations but most important is the fact that in replenishing the reloading magazine of a feeder, operation of the latter is interrupted and many impressions are lost. While this condition has long been recognized and efforts made to correct it, such attachments which have materialized as a result are comparatively complex and require certain alterations in a press feeder for their installation and use, a fact which is highly objectionable to the machine owner.

The principal object of the invention is to provide an auxiliary reloading plate or panel for press feeders which is extremely simple in construction and which may be used by a pressman for reloading the feeder magazine at any time at his option and without the necessity for permanently attaching the plate to the machine.

Another object of the invention is to provide an auxiliary reloading plate or panel for press feeders which consists of a stock separator plate of a length equal to the width of the reloading magazine of a press feeder and having on each end a lug equipped with means to effect its releasable attachment to the slide frame castings of the feeder magazine. The auxiliary reloading panel, in clamped position, is adapted to occupy the position of the elevator advancing plate while the latter is being retracted preparatory to replenishing the partially depleted magazine and functions to retain the remaining stock in the magazine in feeding position and following the replenishing operation, the auxiliary panel is completely removed from the magazine until again needed for a like operation.

With the foregoing objects in view, the invention has further reference to certain features of accomplishment which will become apparent as the description proceeds, taken in connection with the accompanying drawing wherein:

Figure 1 is a perspective view of an auxiliary reloading panel per se, constructed according to the present invention.

Figure 2 is a perspective view of a press feeder magazine showing two auxiliary reloading panels therein, although but a single panel is ordinarily required, and

Figure 3 is a view of a press feeder magazine in longitudinal section also showing two auxiliary reloading panels operatively arranged therein.

Continuing with a more detailed description 55

2

of the drawing reference numeral 10 denotes the base plate of a press feeder magazine which is normally inclined in relation to the receiving station of a press feeder, not shown. On each side of the base plate 10 is an elevator slide frame casting 11 supported on the plate by brackets 12 at their ends. These slide members 11 have confronting grooves 13 (Fig. 3) receiving the ends of the elevator shaft 14.

The elevator advancing plate 15 has formed thereon a pair of bosses 16 which are bored to receive the rod or shaft 14 and this plate is advanced upwardly along the magazine base plate 10 when tapes 17 adjacent the slide members 11 are wound on a ratchet shaft 18 at the upper end of the magazine. The ratchet shaft 18 is actuated by a gear mechanism in the housing 19, so that upward movement of the elevator advancing plate 15 may be regulated in feeding stock to the grippers or suckers of the press feeder.

The illustration is that of the conventional Kluge press feeder, on which the invention is designed to operate and since the construction and operation of this machine is well known to those versed in the art, further description thereof is considered unnecessary to a full understanding of the construction and purpose of the present invention.

Accordingly, the invention consists of a panel 20, as shown separately in Figure 1, lower portions of which are cut away to define extensions 21 at each end which are adapted to overlie the elevator slide frame casting 11 in the manner shown in Figure 2, and to further define a portion 22 at the midsection of the panel which depends into almost touching engagement with the magazine base plate 10.

At each end of the panel 20 is an offset or stepped lug 23, having a bifurcated upper end receiving the extension 21 of the panel 20 and which is secured thereto by means of rivets or pins 24. The offset portions of the lugs 23 provide shoulders *a* which are adapted to rest on the slide frame castings 11 and the lower ends of the lugs, are each provided with an internally threaded aperture adapted to receive a thumb screw 25, although but one such screw is actually necessary as will become apparent presently.

Detachably and interchangeably mountable on the panel 20 is a group of spring steel clips 26 and 27. The clips are of identical construction but are designated by different reference numerals to better reveal their function. The panel 20 is cut away as explained, to expose as little area as possible to the stock in the magazine and the

spring clips 27 are slidably attached to the panel and extend downwardly on the face of the panel confronting the stock and have an effect to thrust the lower portion of the stock slightly forward and thus reduce friction of the latter where it is advanced along the base plate 10 as the panel is manually shifted into position against the stock preliminary to securing of the panel by the thumb screws 25, as will be explained. The upwardly extending clips 26 are used only when the width or height of the stock is such that it extends well above the panel 20 in the magazine and their presence insures perpendicularity of the stock with respect to the base plate 10. Both the clips 26 and 27 may be longitudinally adjusted on the panel 20 when the nature of the stock may require changes in position of the clips for better feeding performance.

In operation, a pressman will fill the space between the elevator advancing plate 15 and the feeding point of the magazine with stock. This may be done while the press feeder is either operating or idle. The feeder is then set to feeding, the suckers transferring stock sheets singly from the magazine into the press. As the magazine stock diminishes, the elevator advancing plate 15 moves upwardly.

It happens frequently that a pressman attending to other duties will either neglect to replenish the magazine or will find it impossible to at once attend to the reloading thereof. In any such case, the feeder continues to operate but many impressions are lost, resulting in a financial loss to the printer through loss of time.

A pressman equipped with the invention has simply to dispose the panel 20 between the elevator advancing plate 15 and the stock being advanced thereby and to secure the panel 20 by turning one of the thumb screws 25. Two of such screws are shown by one is ordinarily sufficient to hold the panel 20 during the brief period when the elevator advancing plate 15 is returned to its original starting position at the rear of the magazine. While the auxiliary panel 20 retains the remaining stock in feeding position, the pressman will obtain additional stock and place the same between the remaining stock and the advancing plate 15, after which he will release the latter for feeding and will loosen the screw 25 and remove the auxiliary panel 20 entirely from the magazine. The panel 20 is not again used until the pressman finds it expedient to again replenish the magazine which he does at his time and option.

It is clearly apparent from the foregoing that without altering or defacing his press feeder in any manner, a pressman may speed up his output, especially during long runs, by employing the invention in the manner described.

Manifestly, the construction as shown and described is capable of some modification and such modification as may be construed to fall within the scope and meaning of the appended claims is also considered to be within the spirit and intent of the invention.

What is claimed is:

1. In combination with the reloading magazine and elevator advancing plate of a press feeder, an auxiliary reloading unit comprising a panel adapted to be interposed in a partially depleted reloading magazine between the stock therein and the elevator advancing plate, a lug affixed to each end of said panel, each of said lugs having a shoulder adapted to rest upon the slide frame casting of said press feeder, a set screw in said lug below said shoulder adapted to engage said slide frame casting for temporarily securing said panel to hold the stock in feeding position in said magazine during retraction of said elevator advancing plate and interchangeable means adjustably carried by said panel for minimizing friction between the stock and the base plate of said magazine when said panel is being manually shifted into operative position.

2. In combination with the reloading magazine and elevator advancing plate of press feeder, an auxiliary reloading unit comprising a panel having an extension at each end adapted to over-reach the elevator slide frame casting of said magazine, a stepped lug on the end of each of said panel extensions engaging said slide frame castings to support said panel between diminished stock in said magazine and said elevator advancing plate to hold said stock in feeding position during retraction of said advancing plate for replenishment of said magazine, means on said panel lugs to clamp said panel onto said slide frame castings, and means comprising spring clips interchangeable and adjustably mounted on the panel to engage and relieve the stock of friction at its point of contact with the base of the reloading magazine when said panel is manually moved to dispose the same operatively against the stock.
